UNITED STATES PATENT OFFICE.

JOHN JAMES BITTLESTONE AND HENRY THOMAS JOHNSON, OF SUNDERLAND,
ENGLAND.

SHIP.

1,282,371.

Specification of Letters Patent.

Patented Oct. 22, 1918.

Application filed February 12, 1916. Serial No. 77,853.

To all whom it may concern:

Be it known that we, JOHN JAMES BITTLESTONE and HENRY THOMAS JOHNSON, subjects of the King of Great Britain and Ireland, residing at Sunderland, in the county of Durham, England, have invented new and useful Improvements in or Relating to Ships, of which the following is a specification.

This invention relates to ships, and has for its object to provide an improved form 10 of inner skin therefor. The invention is applicable to ships of any type, including passenger vessels, but has been particularly designed for application to vessels for carrying 15 oil and other liquids.

According to this invention we provide a ship with an inner skin at each side composed of continuous plating shaped to form a series of alternate vertical bulges and recesses, the plating of the inner skin at each side of the vessel being preferably built up 20 as a separate structure but being preferably one structure throughout its length. Transverse bulkheads may be provided between 25 said inner skins and the adjacent sides of the ship and also between said inner skins across the central portion of the ship.

We will fully describe our invention with reference to the accompanying drawings 30 wherein

Figure 1 is a diagrammatic plan of a ship provided with our improved construction of inner skins; and

Figs. 2 and 3 are part similar views to Fig. 1 illustrating modifications.

Referring to Fig. 1 of the drawings, we provide the ship with an inner skin *a* at each side of the vessel composed of plates curved and connected together so as to form a series 40 of alternate vertical bulges *b* and recesses *c*. The inner skins *a* may extend the full length of the vessel or they may only extend for a portion of the length. In the example illustrated in Fig. 1, the inner skins 45 extend from the fore-peak bulkhead *d* to the bulkhead *e* dividing the cargo space from the boilers, engines and the like which in this case are arranged in the stern of the vessel. The radii to which the plating of the inner skins *a* is set to form the alternate 50 vertical bulges and recesses may vary as the width of the ship varies, or to meet special circumstances. In the example illustrated the radius of the bulges *b* is approximately 55 equal to half the width of the ship, the centers from which the curves are struck being

off-set from the center line of the ship. As shown in the drawings, each of said corrugations and recesses taken together is nearly equal to the beam of the vessel, that is, the 60 length of the hull opposite a corrugation and an adjoining recess is equal or nearly equal to the average beam of the hull at that point, as will be seen very clearly from the drawing and particularly from Fig. 3, where the 65 transverse bulkheads *k*, *o*, *p*, with the sides *g* extending between the bulkheads, define practically a square. Spaces *f* are thus formed between the inner skins *a* and the sides *g* of the vessel. The inner skins *a* may 70 extend from the bottom or inner bottom of the ship to the lower deck or as may be required, and may be connected to the sides *g* where required by frames or like devices. If desired the plates of the inner skins may be 75 corrugated instead of plane.

Where they end, the inner skins *a* may be connected to a transverse bulkhead such as the bulkhead *e* as indicated at the left-hand end of Fig. 1. Or the plating of the inner 80 skins *a* may be curved in toward the center line of the ship and connected together as indicated at *h* at the right-hand end of Fig. 1, and the curved end connection *h* may be connected by a short amidships bulkhead *j* to a 85 transverse bulkhead, for example the fore-peak bulkhead *d*.

It will be seen that throughout its length the inner skin at each side of the vessel is formed of continuous plating and the plating of the inner skin at one side of the vessel is independent throughout its length of the plating of the inner skin at the other side of the vessel, though, as last described, the plating of the two inner skins may be 95 sometimes connected together at their ends.

The central space within the inner skins *a* may be divided into independent compartments or holds. For example, as indicated in Fig. 2, we may provide transverse bulkheads *k*, said bulkheads preferably extending between the recesses *c* where the inner skins *a* approach closest together, as shown. The central portion of the ship will thus be 100 divided into a number of holds *m*.

The spaces *f* between the inner skins *a* and the sides *g* of the ship may also be divided into independent compartments by transverse bulkheads *o* which may be arranged between the vertical bulges *b* and the 110 sides *g* at the points where the inner skins *a* approach closest to the sides *g* as shown in

Fig. 2, or may be arranged in line with the central transverse bulkheads *k* as shown in Fig. 3, or otherwise conveniently. Where the transverse bulkheads *o* are in line with the bulkheads *k* as illustrated at the left-hand of Fig. 3, there is no break in the continuity of the plating of the inner skins *a* as the latter pass through between the ends of the transverse bulkheads *k* and *o*, but in some cases and as shown at the right-hand of Fig. 3, a single bulkhead *p* may be provided extending from side to side of the ship, the plating of the inner skins *a* being connected to said bulkhead at either side thereof.

The spaces *f* between the inner skins and the sides *g* of the ship may be used for cargo, and may conveniently be used for carrying water ballast when no cargo is being carried. In cases where heavy cargoes, such as iron ore or heavy oils are being carried, the spaces *f* will be void of cargo, the cargo being confined within the inner skins, and the load will thus be arranged in a manner tending to improve the stability of the vessel. When cargoes, such as grain, light oils or other liquids, are being carried, the spaces *f* will be utilized as cargo spaces.

The inner skins will tend to safeguard the vessel from dangerous flooding in the case of collision or damage. Where the spaces *f* are divided into independent watertight compartments as above described, should a compartment at one side be flooded and cause the vessel to list to that side, a compartment at the other side may be flooded to counterbalance the first flooded compartment, any known means being provided for admitting water to the compartments for this purpose.

By the peculiar construction of our improved inner skin less weight of material is required than in plane inner skins to give equal strength as the usual stiffeners necessary to support a plane inner skin are dispensed with, and the cost of construction is further reduced because there are fewer riveted connections in our improved inner skin than in a plane inner skin. Moreover the longitudinal strength of the ship is increased. As no horizontally projecting stiffeners are employed in our construction, improved ventilation is obtained and the compartments between the inner skins and the sides of the ship are more readily cleaned. No center line division of the ship is necessary, and our improved construction tends to more advantageous loading where heavy cargoes are carried as the cargo can be more evenly distributed throughout the length of cargo space than has hitherto been possible.

What we claim and desire to secure by Letters Patent is:—

1. In a ship, an interior construction involving a fore-peak bulkhead, a bulkhead dividing the cargo space from the engine

and boilers, and a corrugated inner skin on each side of the ship having alternate vertical bulges and recesses disposed between said bulkheads, each of said bulges and recesses taken together being nearly equal to the beam of the vessel, the radius of said bulges being approximately equal to half the width of the ship.

2. In a ship, an interior construction involving a fore-peak bulkhead, a bulkhead dividing the cargo space from the engine and boilers, and a corrugated inner skin on each side of the ship having alternate vertical bulges and recesses disposed between said bulkheads, and transverse bulkheads disposed between the said recesses, each of said bulges and recesses taken together being nearly equal to the beam of the vessel the radius of said bulges being approximately equal to half the width of the ship.

3. In a ship, an interior construction involving a fore-peak bulkhead, a bulkhead dividing the cargo space from the engine and boilers, and a corrugated inner skin on each side of the ship having alternate vertical bulges and recesses disposed between said bulkheads, and transverse bulkheads disposed between the said recesses, and transverse bulkheads disposed between the said recesses and the sides of the ship, each of said bulges and recesses taken together being nearly equal to the beam of the vessel, the radius of said bulges being approximately equal to half the width of the ship.

4. In a ship, an interior construction involving a fore-peak bulkhead, a bulkhead dividing the cargo space from the engine and boilers, and a corrugated inner skin on each side of the ship having alternate vertical bulges and recesses disposed between said bulkheads, and transverse bulkheads disposed between said bulges and the sides of the ship, and transverse bulkheads disposed between said recesses, each of said bulges and recesses taken together being nearly equal to the beam of the vessel the radius of said bulges being approximately equal to half the width of the ship.

5. In a ship, an interior construction involving a fore-peak bulkhead, a bulkhead dividing the cargo space from the engine and boilers, and a corrugated inner skin on each side of the ship having alternate vertical bulges and recesses disposed between said bulkheads, and transverse bulkheads extending across the central portion of the ship and transverse bulkheads extending between the inner skins and the adjacent sides of the ship said side transverse bulkheads being in line with said central transverse bulkheads and meeting the inner skins at the point where these approach closest together, each of said bulges and recesses taken together being nearly equal to the beam of the vessel the radius of said bulges being

approximately equal to half the width of the ship.

6. In a ship, an interior construction involving a fore-peak bulkhead, a bulkhead 5 dividing the cargo space from the engine and boilers, and a corrugated inner skin on each side of the ship having alternate vertical bulges and recesses disposed between said bulkheads, said two inner skins at the 10 forward end of the vessel forming a large bulge such as h , each of said bulges and recesses taken together being nearly equal to

the beam of the vessel the radius of said bulges being approximately equal to half the width of the ship.

In testimony whereof we have signed our names to this specification in the presence of two subscribing witnesses.

JOHN JAMES BITTLESTONE.
HENRY THOMAS JOHNSON.
